United States Patent Office.

LUTHER BOYD AND PHILIP KRIEGBAUM, OF SPRINGFIELD, OHIO.

Letters Patent No. 70,689, dated November 12, 1867.

CAR-CO尤LING.

The Schedule referred to in these Letters Patent and making part of the same.

TO ALL WHOM IT MAY CONCERN:

Be it known that we, LUTHER BOYD and PHILIP KRIEGBAUM, of Springfield, in the State of Ohio, have invented certain new and useful improvements in Car-Couplings; and we do hereby declare that the following is a clear, full, and exact description of the same, reference being had to the accompanying drawings, and to the letters of reference marked thereon, in which—

Figure 1 represents a side elevation of the coupling, and

Figure 2 a plan of the same.

The nature of this invention consists in the employment of a movable head, so arranged with relation to the other parts of the coupling that it will overcome in a great measure the jar or shock of two cars coming together.

A represents the main body of the coupling, provided with the recess *g*, and the stationary head *C*. *b* is a box, in which the pin or bolt *f* rests. *B* represents the movable head, the shape of which is clearly shown in fig. 2. *e e* are slides, which work in slots provided for them in the stationary head *C*. Said slides are securely attached at their front ends to the movable head *B*, while their opposite ends rest against springs *d d*. It should be observed that the front portion of these slides are flat, and their opposite ends round, as seen in fig. 1. The springs *d d* should be enclosed in a cylindrical box. *i i* represent holes in the slides for the reception of the pin. When said slides are forced back sufficiently to bring the holes *i i* directly in line with holes *h h*, the pin drops in them, and retains the movable head *B* in the position indicated in fig. 2. The opening or mouth of the movable head should, of course, be flared, in order to direct the link, which is of the ordinary kind, to its proper place.

It will be noticed that our invention will not only prevent in a great measure the shock of two cars coming together, but it will assist, when they are at rest and the pin is removed, to start them.

What we claim, is—

The movable head *B*, as constructed in combination with stationary head *C*, slides *e e*, and springs *d d*, all arranged and operating in the manner and for the purpose herein set forth and described.

In testimony whereof we affix our signatures in presence of two witnesses.

LUTHER BOYD,
PHILIP KRIEGBAUM.
